UNITED STATES PATENT OFFICE

2,235,987

DISPENSING CONTAINER CLOSURE

Emil Frank, Cincinnati, Ohio

Application June 8, 1939, Serial No. 278,099

2 Claims. (Cl. 221—62)

My invention relates to dispensing container closures wherein by the movement of a sliding member sifting or dispensing openings in a wall of a metallic container is provided. In my Patent No. 2,162,999, dated June 20, 1939, I disclosed a container having a top wall with a segmental opening therein, the chord of which is greater than the thickness of the container, and a slide for closing the opening having an edge parallel with the chord of the arc of the segmental opening and perforations in the slide conforming to the arc of the opening. This application is a continuation in part of my Patent No. 2,162,999.

It is an object of my invention to describe one of the various modifications of closure openings susceptible for use with the inventive features of my invention as set forth in my patent hereinbefore referred to.

It is an object of my invention to provide improvements in dispensing closures wherein the sliding member forming the closure is held in position during one of the normal operations of the can construction.

It is an object of my invention to provide an improved dispensing opening closure which will be inexpensive, non-luable to become displaced, and in which the manipulation of the closure may be simply accomplished.

The above objects and other objects to which reference will be made in the ensuing description, I accomplish by that certain construction and arrangement of parts of which I have illustrated a preferred embodiment.

Referring to the drawing:

Figure 1 is a perspective view of one type of dispensing opening closure in a metal can.

Fig. 2 is a sectional view of the can illustrated in Fig. 1, taken along the lines 2—2 of Fig. 1.

Fig. 3 is a perspective view of a slightly modified type of closure.

Fig. 4 is a lateral sectional view of the can illustrated in Fig. 3 taken along the lines 4—4.

Fig. 5 is a longitudinal sectional view of the combination of parts forming the end closure for the can top illustrated in Fig. 3 taken along the lines 5—5.

Referring first to Figs. 1 and 2, the container is illustrated having side walls 1, end walls 2 and a top wall 3, the end and side walls being secured in position by the downward crimping of side edges of the top wall as indicated at 4. Such construction is standard and forms no part

of my invention. The particular can to which I have applied my invention has a capacity of 1½ ounces of pepper and has dimensions as follows: side walls—2 by 3 inches—end walls—1 by 3 inches and top wall 1 by 2 inches. The main surface 5 of the top wall is depressed about $\frac{1}{8}$ inch. It will be obvious that in such construction it is not possible to make a dispensing opening for accommodating a teaspoon by cutting a hole in the top wall of segmentary shape with the chord 10 of the segment extending across the width of the container, because a chord extending across the bowl of a teaspoon is normally over 1¼ inches long.

Accordingly I arrange a segmentary opening 15 in the top wall of the container, the chord 5 of the segment extending diagonally across the container, the arc 6 of the segment, extending from the ends of the chord, being also diagonally 20 positioned.

In Figs. 1 and 2 the can illustrated has a top wall spaced from the upper edges of the top walls of the can and crimped-in guides 7 which hold in position a slide member having a body 25 8, and an actuating handle 9 formed by curling up a tongue projecting from the end of the slide member. The top wall has an indented ledge 10 which limits the forward movement of the sliding member by abutment of the front edge 30 of the slide member.

In the modifications shown in Figures 3 to 5, the construction is substantially the same as in Figures 1 and 2 excepting that the side edges 11, 12 of the slide member generally indicated 35 at 8a are bent downwardly as best illustrated in Figure 4. I find that this curling downwardly of the side edges of the slide member prevents the slide member from sticking in the guides 1. Further as a preferred type of intermediate stop 40 to hold the slide member in dispensing position for sifting, I have found that by cutting a slot 13 in the slide member and crimping a hump or ridge 14 in the top wall of the can it will be easier to set the slide member for sifting position and also set the slide member in fully closed 45 position by abutment of the curled edge of the handle 9.

The continuation subject matter in this case consists in the general arrangement of the can 50 top with the inwardly crimped side guide for the slide member while the improvements specifically shown in Figures 3, 4, 5 relate to the downward curling of the side edges of the slide member and the hump and slot forming a tem- 55

porary stop, as modifications of the general arrangement of parts shown in Figures 1 and 2.

Having thus described by invention, what I claim as new and desire to secure by Letters 5 Patent is:

1. A closure for a container of the character described having side and end walls comprising a top wall member having a dispensing opening therein, a slide member for opening and closing 10 said dispensing opening and said top wall member having peripheral edge portions crimped to the side and end walls of said container, said peripheral edge portions having outwardly extending ribs forming guide channels for restraining said sliding member to a plane of movement 15 parallel with said top wall, said sliding member having downwardly turned side edges for spacing said slide member from the can top and avoiding sticking of said slide member in its movement 20 in said guide channels.

2. A closure for a container of the character described having side and end walls comprising a top wall member having a dispensing opening therein, a slide member for opening and closing 5 said dispensing opening and said top wall member having peripheral edge portions crimped to the side and end walls of said container, said peripheral edge portions having outwardly extending ribs forming guide channels for restraining said sliding member to a plane of movement 10 parallel with said top wall, said sliding member having downwardly turned side edges for spacing said slide member from the can top and avoiding sticking of said slide member in its movement 15 in said guide channels, and said top wall having an upwardly crimped ridge and said slide member having a slit for engaging in said upwardly crimped ridge to restrain said slide member in an intermediate position of sifting dispensing.
